UNITED STATES PATENT OFFICE.

RALPH COLLEY, OF TONICA, ILLINOIS.

DISK-HOLDER.

1,346,004.

Specification of Letters Patent.

Patented July 6, 1920.

Application filed September 19, 1919. Serial No. 324,787.

To all whom it may concern:

Be it known that I, RALPH COLLEY, a citizen of the United States, residing at Tonica, in the county of La Salle and State of Illinois, have invented new and useful Improvements in Disk-Holders, of which the following is a specification.

This invention relates to the grinding art and has for its object the provision of a holder whereby the disk of a harrow may be firmly and properly held in position to be acted upon by a rotary grinding device whereby the disk may be sharpened and properly dressed.

15 An important object is the provision of a device of this character which will be simple and inexpensive in manufacture, highly efficient in service, durable in use, and a general improvement in the art.

20 With the above and other objects and advantages in view, the invention consists in the details of construction to be herein-after more fully described and claimed, and illustrated in the accompanying drawings 25 in which—

Figure 1 is a plan view of my device showing it associated with a grinder,

Fig. 2 is a side elevation thereof,

Fig. 3 is a plan view of the holder with 30 the disk removed,

Fig. 4 is a detail cross sectional view through the axle support for the disk, showing the disk in one position.

Fig. 5 is a similar view showing the disk 35 supported in the reverse position, and

Fig. 6 is a side elevation of the holder frame.

Referring more particularly to the drawings; the letter A designates a supporting 40 table or bench upon which is mounted any preferred or suitable form of grinder B having an abrasive wheel C.

My invention resides in the provision of a holder formed as a triangular shaped 45 frame 10 formed of metal and having preferably wooden handles 11. This frame includes a plate 12 through which extends a circular hole 13.

In order that a harrow disk D may be 50 properly supported upon my device, I provide an axle member 14 which is cylindrical and either end of which is adapted for insertion within the hole 13. Intermediate its

ends the axle 14 is provided with a frusto pyramidal enlargement 15 adapted for engagement within the square opening E provided centrally within the disk D. Adjacent the enlargement 15 the axle 14 is threaded, as shown at 16, and engageable upon this threaded portion is a clamping 55 cup member 17 adapted to engage the disk D for forcing the same onto the inclined sides of the enlargement 15.

In the operation of the device the disk D is placed upon the axle 14 with either its 60 convex or concave sides disposed toward the enlargement 15 and the cup member 17 is threaded onto the axle member into firmly clamping engagement with the disk. Either end of the axle member 14 is then 65 inserted into the hole 13 in the holder, depending upon which side of the disk it is desired to sharpen. The parts being thus 70 assembled the operator grasps the handles 11 and tilts the frame 10 upon its point to 75 bring the edge of the disk in engagement with the grinding wheel C. It will be readily observed that the device may be tilted as desired or required to bring different points on the periphery of the disk into 80 engagement with the wheel. It will also be observed that the disk will be rotated to a certain extent by the action of the grinding wheel so that the entire edge of the disk 85 will be properly dressed. After one side is sharpened the operator removes the disk and axle member as a whole and inserts the other end of the axle member into the holder to bring the other side of the disk 90 uppermost after which the same operation is gone through with.

While I have shown and described the preferred embodiment of my invention it is of course to be understood that I reserve the right to make such changes in the form, 95 construction, and arrangement of parts as will not depart from the spirit of the invention or the scope of the subjoined claim.

Having thus described my invention, I 100 claim:—

A device of the character described comprising a frame provided with handles, a plate secured upon said frame and provided with a hole, an axle member cylindrical and of the same diameter at 105 each end with either end insertible within

said hole, a frusto - pyramidal enlargement formed upon said axle member intermediate the ends thereof and adapted for conforming engagement with the square hole provided in the center of harrow disks, said axle member being provided adjacent said enlargement with a threaded portion, and a

cup member engaged upon said threaded portion and adapted to bear against a harrow disk engaged upon said axle against 10 said enlargement, said cup member having an annular portion engageable by a wrench.

In testimony whereof I affix my signature.
RALPH COLLEY.
